[57] ABSTRACT

A test socket for receiving the stud of a semi conductor for testing, comprising of: four equidistantly disposed upwardly and inwardly extending inclined contact arms, the arms being connected in common to a binding post; four electrical contacts, each secured to the inside of the upper end of a corresponding arm; and manually operated means, actuated after the stud is disposed vertically downward in the center of a space bounded by the arms, to increase the amount of inward inclination of the arms until the contacts engage the stud.

TEST SOCKET FOR STUDDED SEMI CONDUCTORS

SUMMARY OF THE INVENTION

My invention is directed towards a test socket used in testing studded semi conductors which enables electrical testing to be carried out quickly, efficiently and easily with minimum wear or abrasion of stud or socket.

The socket is provided with four equidistantly disposed upwardly and inwardly extending inclined contact arms, the arms being connected in common to a binding post. A separate electrical contact is secured to the inside of the upper end of each arm. Manually operated means, actuated after the stud is disposed vertically downward in the center of a space bounded by the arms, to increase the amount of inward inclination of the arms until the contacts engage the stud whereby testing can be performed.

The means includes a plate, a horizontal shaft rotated by an arm at right angles thereto and a cam on the shaft which produces relative motion between the arms and the plate, the inward inclination being increased when the plate is lowered relative to the arms.

BRIEF DESCRIPTION OF THE DRAWINGS

In the drawings:

FIG. 1 is a cutaway front view of one form of my invention;

FIG. 2 is a cutaway left side view thereof;

FIG. 3 is a top view thereof;

FIG. 4 is a view of a modification thereof; and

FIG. 5 illustrates the connections between the contact arms.

DETAILED DESCRIPTION OF PREFERRED EMBODIMENTS

Referring first to FIGS. 1-3 and 5 a flat horizontal circular base 10 formed for example of molded delrin or polypropylene has a removable hollow cover 12 having a center opening 14 and a bottom flange 16 bolted to the base. A handle mount 18 of like material extends upward from the base.

A horizontal bore 20 in mount 18 accommodates rotatable shaft 22 having an exposed handle 24 disposed at right angles thereto. Both vertical flat nylon cams 26 are secured at off center holes to shaft 22 and rotate therewith. The cams extend at right angles to the shaft. Cam stop 34 prevents any left hand movement toward vertical guide 38.

A horizontal circular pressure plate 28 is disposed above the cam and mount with a center hole 30 which defines an inverted truncated cone. Steel springs 32 extend downward from the plate to brackets 35 adjacent plate stop 36. Plate 28 has a hole through which verti-

cal guide 38 carrying compression spring 40 extends.

An external binding post 42 is connected via terminal lugs and brackets 35 to each of four upwardly and inwardly inclined equidistantly spaced contact arms 44 having contacts 46 at inner top ends. The arms are formed of tempered beryllium copper. The contacts can be gold plated over a nickel strike.

In use a threaded stud of a semi conductor is inserted vertically within the opening 14, the arm 24 is pivoted and the cam forces the plate down bending arms inward until the contacts engage the stud. A voltage is applied between the appropriate terminal or terminals of the semiconductor and the binding post to perform the appropriate electrical test or tests.

FIG. 4 shows a modification in which the plate 28 is secured pivotally by spring steel wire 60 to the arms 44 and is supported by an integral vertical shaft 62 movable in vertical bore 64 of housing 66 of delrin or the like. The bottom ends of the arms are secured to an upper base 10' and the bore extends to a bottom base 10''. The cam when rotated can pass through slot 68. The same cover as used in FIGS. 1-3 can be used. The rotation of the arm 24 forces the contact engagement with the stud and the test proceeds as before.

While I have described my invention with particular reference to the drawings, such is not to be considered as limiting its actual scope.

Having thus described this invention, what is asserted as new is:

1. A test socket for receiving the stud of a studded semiconductor for testing comprising:

a hollow electrically nonconductive structure having a top horizontal opening through which the stud extends;

four equidistantly disposed upwardly and inwardly extending inclined contact arms in the structure, said arms being connected in common to a binding post;

four electrical contacts in the structure, each secured on the inside of the upper end of a corresponding arm; and

manually operated means in the structure, actuated after said stud is disposed vertically downward in the center of a space bounded by the arms to increase the amount of inward inclination of the arms until said contacts engage the stud, said means including a plate disposed horizontally in the space, spring wire securing said plate to said arms, a horizontal shaft rotated by an arm extending at right angles thereto, and cams on the shaft which produces relative motion between said arms and the plate, whereby lowering the plate relative to the arms increases said inward inclination.
